CAN OPENER

Thomas L. Rush, Cleveland, Ohio

Application February 8, 1946, Serial No. 646,254

3 Claims. (Cl. 30—9)

1

My invention relates in general to can openers and, more particularly, to a can opener of the type in which a rotatable traction element is arranged to engage and effect rotation of a can, and a cutting blade is extended into such can to cut out its top along the side of the bead thereof.

The general object of my invention is to provide a can opener of the character described which can be easily and inexpensively manufactured from few parts and requires no adjustment for cans of different shapes, sizes and dimensions.

Such a general object according to this invention is attained by a can opener embodying cutting blade supporting means and traction element supporting means slidably coupled with each other at horizontally spaced areas to permit changes in the relative position of the blade and the traction elements by sliding and yielding action of these elements with respect to each other and thus insure proper and easy operation of the can opener.

Another object of the invention therefore is to provide a can opener embodying a cutting blade supporting base member, a traction element supporting slide member, and coupling means slidably coupling said members with each other, in which opener the base member, slide member and coupling means are cooperating to permit changes in the relative position of blade and traction element for opening of cans having different shapes, sizes and dimensions and cans having rims varying in thickness.

A further object of the invention is to provide a can opener embodying a cutting blade supporting base member, a traction element supporting member slidably coupled with said base member and yielding means on said slide member adapted to engage the top edge of the rim of a can, the said yielding means facilitating positioning of the can between blade and traction element and permitting use of the opener on cans with rims varying in height.

In addition, the invention has other marked improvements and superiorities which radically distinguish it from presently known structures. These improvements or superior characteristics embodying certain novel features of construction are clearly set forth in the appended claims; and a preferred embodiment of the invention is hereinafter shown with reference to the accompanying drawing forming part of the specification.

In the drawing:

Fig. 1 is a side-view of a can opener constructed

2

in accordance with the invention, the view showing the can engaging side of the opener.

Fig. 2 is a front view of the can opener shown in Fig. 1.

Fig. 3 is a plan view of the can opener shown in Fig. 1, the view showing the can opener in can opening operations.

Fig. 4 is a side-view of the can opener as shown in Fig. 3, disclosing the handle side of the can opener.

Fig. 5 is a side-view of the traction element supporting slide member.

Fig. 6 is a fragmentary side-view of the cutting blade supporting base member; and

Fig. 7 is a perspective view of a somewhat modified form of a traction element supporting slide member.

Referring now more particularly to the accompanying drawing which illustrates a preferred embodiment of the invention, reference numeral 2 denotes an elongated base plate adapted to be removably mounted on a bracket 3. Base plate 2 carries near its one end a tubular, partly slotted member 4 sleeved with its slotted portion 5 on

plate 2 and secured thereto in any suitable manner. The downwardly extended portion 6 of tubular member 4 forms a pivot arm cooperating with bracket 3 in non-rotatably supporting base plate 2 when portion 6 is extended into the sleeve

30 7 of said bracket and the lower edge of plate 2 is rested in a slot 8 of said sleeve. Base plate 2 furthermore includes an enlarged portion 9 including a substantially rectangularly shaped substantial cut-out 10, which portion mounts above 35 said cut-out on strip-like portion 11 a disc-shaped cutting blade 12 rotatably mounted on a pin 14 and positioned to extend partly opposite to cut-out 10 and permit cooperation of said cutting blade with a traction element 15, as will be described hereinafter.

Base plate 2 supports and is interengaged with a somewhat triangularly shaped slide 16 which is slidably supported on pins 17 of base plate 2, the pins being extended through elongated slots

45 18 in said slide. This slide is formed at its top portion with an elongated slot 19 through which extends the cutting blade mounting strip-like portion 11 of base plate 2. Slide 16 is formed with laterally extended top and bottom flanges, top flange 20 being of substantial length and extended laterally opposite slot 18, and bottom flange 21, which is considerably shorter than top flange 20, being shaped to taper off toward the rear. The central area of slide 16 rotatably 50 mounts the traction element 15 arranged in axial

alignment with elongated slots 18. This element which consists of a hardened steel disc with a toothed peripheral edge, is mounted to extend into and rotate in cut-out 19 of base plate 2 and is rigidly coupled with a crank 23 arranged at the other side of slide 16.

The top and bottom flanges 20 and 21 of slide 16 serve to space the can to be opened with respect to cutting blade 12, prevent angular displacement of the can during opening operations, and effect proper angular relation between cutting blade and can and thus insure a smooth-edged cut adjacent to the bead of the can. Top flange 20 is dimensioned and constructed to yield to permit cutting operations on cans with rims of various heights and irregularities on such rims, and to that effect is positioned opposite slot 19 to give said flange the shape of a long and narrow strip supported only at opposite ends. Such a strip readily yields and permits cutting operations on cans with rims of various heights without excessive strain and deformation of the strip. Bottom flange 21 is tapered off toward the supporting end of base plate 2 to facilitate engagement of a can with cutting blade 12 and effect proper angular relation between said blade and the can during cutting operations.

In addition, cutting blade 12 is yieldingly supported so as to permit its lateral yield with respect to traction element 15 for cutting operations on cans with rims of various thickness and smooth cutting of a can cover adjacent to its seam. Such yielding support of the blade is attained by mounting cutting blade 12 in the central area of strip-like portion 11 of base plate 2, which portion is supported only at its opposite ends and under stress yields to permit a lateral yield of cutting blade 12 necessary for cutting operations on cans having rims of various thickness.

In can opening operations a can is placed against top flange 20 so that cutting blade 12 engages the inner face of the can rim and then crank 23 is moved forward to shift traction element 15 on slide 16 into frictional operative engagement with the can bead. In this position rotation of traction element 15 by its crank 23 causes the can top to be moved and pierced and sheared by cutting blade 12, which blade is constrained against the inner surface of the can bead to shear the can top close to the bead.

The modified construction shown in Fig. 7 discloses a slide 24 constructed in general similar to slide 16 previously described, with the exception that slide 24 has attached to its top portion 25 a leaf-spring member 26. This member, which takes the place of the top flange 20 of slide 16, includes at its front end a lateral extension 27 to facilitate engagement of the member with a can and is rigidly secured with its rear end to slide 24, yields more readily and permits general

use of a can opener thus equipped for opening all types of cans, even those with rims substantially varying in heights.

Having thus described my invention, what I claim is:

- 5 1. In a can opener, a base member having an elongated hole, a cutting blade mounted on one side of said base member midway above said elongated hole so as to extend partly opposite said elongated hole, an elongated slide member shiftably coupled with said base member, a traction element rotatably mounted on said slide member so as to extend within said elongated hole of said base member, and laterally spaced means shiftably connecting said slide member with said base member, said spaced means arranged to limit shifting of said slide member to hold the traction wheel in all possible positions within the elongated hole of said base member.
- 10 2. In a can opener a base member having an elongated hole arranged and dimensioned to provide a strip-like part above said hole, a cutting blade mounted on said strip-like part midway thereof so as to extend partly opposite said hole, an elongated slide means shiftably attached to said base member, and a traction element mounted on said shiftable means and extending into said hole of said base member, said strip-like part yieldingly spacing the cutting blade and traction element with respect to each other to permit proper opening of cans having rims of various thickness.
- 15 3. In a can opener a base member having an elongated hole arranged so as to provide a strip-like laterally yielding part above said hole midway thereof, a cutting blade mounted on the central portion of said strip-like part so as to partly extend opposite said hole, a slide member shiftably secured to said base member, a traction element rotatably mounted on said slide member so as to be extended into the hole of said base member, means shiftably connecting said slide member to said base member, and a vertically yielding, can-engaging, strip-like portion laterally extending from the upper portion of said slide member to yieldingly engage the top edge of the rim of a can to be opened, the strip-like part permitting lateral yield of said cutting blade for cans having rims of various thickness, and the can-engaging, strip-like portion permitting vertical yield for cans having rims of various heights.
